UNITED STATES PATENT OFFICE.

HOWARD S. DITSCH, OF DAYTON, OHIO.

DESIGN FOR A FIGURE TOY.

Application filed February 9, 1924. Serial No. 8,588. Term of patent 7 years.

To all whom it may concern:

Be it known that I, HOWARD S. DITSCH, a citizen of the United States, residing at Dayton, in the county of Montgomery and State of Ohio, have invented a new, original, and ornamental Design for Figure Toy, of which the following is a specification, reference being had to the accompanying drawing, forming part thereof.

Fig. 1 is a top plan view of a figure toy illustrating my new design.

Fig. 2 is a side elevation and

Fig. 3 is a front elevation of the same.

I claim:

The ornamental design for a figure toy, as shown.

HOWARD S. DITSCH.
